UNITED STATES PATENT OFFICE.

VICENTE SANCHEZ, OF PONEMAH, ILLINOIS.

ORE-GRADING MACHINE.

Application filed November 11, 1927. Serial No. 232,555.

This invention relates to a new and useful device in the nature of an ore grading machine especially adapted for the purpose of grading in classifying ore according to the various sizes of the said ore, which is necessary at the mine prior to the use or shipment of the said ore.

The object of the invention is to provide an ore grading machine of novel construction and arrangement of parts hereinafter more fully described, claimed and illustrated in the accompanying drawing.

A further object of the invention is to provide an ore grading machine embodying certain novel adjustable features hereinafter more fully set forth and described in detail.

Fig. 1 is a side elevational view of my improved ore grading machine.

Fig. 2 is a top plan view thereof.

Fig. 3 is an enlarged detail view of the adjustable gate as embodied in my improved device.

Fig. 4 is a top plan view of the adjustable screen shutter as embodied in my improved device.

Fig. 5 is a longitudinal sectional view taken on the line 5—5 of Fig. 4.

Fig. 6 is a transverse sectional view taken on the line 6—6 of Fig. 4.

As here embodied my improved ore grading machine comprises a link belt conveyor, consisting of a pair of endless link belts 10 and 11, extended over suitable sprocket wheels 12, 13, 14 and 15 respectively, secured to the shafts 16 and 17. Brackets 11', or scoops secured to the said link belts 10 and 11, are extended transversely therefrom. The shaft 16 is rotatively mounted in suitable bearings 18 and 19, mounted on the upright members 20 and 21, secured to and extended from the hopper 22, of box like construction. The shaft 17, is rotatively mounted in suitable bearings 23 and 24, mounted on the upright members 25 and 26, which may be of any desired length or height, and which are secured, at their lower extremities to the base members 27 and 28, which are also secured to the hopper 22. Supporting members 29 and 30, are secured at their upper extremities to the top of the upright members 25 and 26, and are angularly disposed downwardly therefrom, and are secured at their lower extended extremities to the base members 27 and 28.

The hopper 31 is mounted on the upper portion of the supporting members 29 and

30, and is positioned partially below the sprockets 13 and 15.

The bevel gear 32, is secured to the shaft 17 and meshes with a bevel gear 33, secured to the shaft 34, rotatively mounted in the bearings 35 and 36, secured to the upright member 26.

The above described construction is such as will permit the ore placed in the hopper 22 to be conveyed into the hopper 31, when the shaft 34 is rotated by any desired means, preferably by an electric motor operatively connected to the shaft 34.

The hopper 31, is provided with an open lower end, adapted to receive the gate 37, of suitable size to close the said lower end of the hopper 31. The gate 37, is pivotally secured as at 38, by a pin or the like, carried in the lug element 39 of the side of the hopper 31, and is provided with a segment gear 40, adapted to mesh with the gear 41, secured to the shaft 42, rotatively mounted in the brackets 43, secured to the hopper 31. The bevel gear 44, is secured to the shaft 42, and meshes with the bevel pinion 45, secured to the shaft 46, rotatively mounted in the bracket 47, secured to the hopper 31, and in the bracket 48 secured to the member 49. The hand wheel 50 is secured to the lower extremity of the shaft 46. The above described construction is such as will permit the gate 37 to be pivotally opened by rotating the hand wheel 50, as designated by the reference numeral 51, for the purpose as hereinafter set forth.

A plurality of screens 52, are secured to the supporting members 29 and 30, the said screens 52, being of comparatively heavy wire mesh, so as to provide the desired rigidity, and are of various mesh, the upper or top screen being of comparatively fine mesh, the lower screen being of coarse mesh, the intermediate screens being graded, as regards the mesh thereof.

Side members 53 and 54, are secured to the supporting members 29 and 30, and extend from the hopper 31, into proximity to the lower extremities of the said supporting members. Partitions 55 extend from the upper and lower extremities of the screen 52, downwardly therefrom and are secured to the base members 27 and 28, side members 56 and 57, being secured to the lower extended extremities of the partitions 55, as a means of providing bins, or compartments under the said screens 52. The above de-

scribed construction is such as will permit the ore, when released from the hopper 31, by opening the gate 37, as above set forth, to roll or fall downwardly therefrom over the screens 52, which will permit the said ore to be graded or divided into practically similar sized pieces, and fall into the said bins below the screens 52.

The shutters 58, are pivotally attached, at one extremity, as at 59, by a pin or the like, secured to the screen 52, and have formed thereon, at their extended extremities, segment teeth 60, adapted to mesh with the gear 61, secured to the shafts 62, rotatively mounted in the brackets 63, secured to the side members 53. The hand wheels 64, are secured to the lower extended extremities of the shafts 62. The side member 53, has formed therein elongated openings adapted to slidably engage the shutters 58. The above described construction is such as will permit the shutters 58, to be pivotally extended, as may be desired, partially over the screens 52, as a means of limiting the usefulness of the said screens 52, as is desirable for ores of various sizes, which do not require the whole amount of screening as is provided, and which will increase the rate of grading of the said ore.

Expansion springs 71 and 72, are secured to the brackets 73 and 74, respectively, attached to the side member 53, and are positioned in the cup members 75 and 76, respectively. The cup members 75 and 76, have formed therein, elongated apertures 77 and 78, respectively, adapted to receive the screws 79 and 80, as a means of slidably attaching the cup members 75 and 76, to the side member 53. The above described construction is such as will permit the springs 71 and 72, to hold the shutters 58 in engagement or in contact with the screens 52, as a means of preventing particles of the ore which may lodge on the screens 52 from interfering with the movement of the said shutters 58.

Extended members 65, are hinged as at 66,

to the inner edge of the shutters 58. The thumb screws 66, are threadedly mounted in the side member 53. The tension springs 67, are secured to the thumb screws 66, and to the lug elements 68 of the extended members 65. The above described construction is such as will permit the extended members 65, to be raised in a vertical position as designated by the reference numeral 69 when the shutters 58, are extended over the screens 52, as designated by the reference numeral 70. The above described construction is such as will prevent the ore from falling or rolling over the shutters 58, when in an extended position.

Having thus described my invention, what I claim as new and desire to protect by Letters Patent of the United States is as follows:

1. In a device of the class described, a screen, a shutter adapted for manual operation, and extended member hinged to the inner edge of the shutter, and a means for elevating said member when the shutter is projected over the screen.

2. In a device of the class described, a screen, a shutter adapted for manual operation, an extended member hinged to the inner edge of the shutter, a lug element projecting therefrom, a tension spring attached to the lug element and arranged for elevating the said member when the shutter is projected over the screen.

3. In a device of the class described, a screen, a shutter adapted for manual operation, an extended member hinged to the inner edge of the shutter, a means for holding the shutter in contact with the screen, a lug element projecting therefrom, a tension spring attached to the lug element and arranged for elevating the said member when the shutter is projected over the screen.

In testimony whereof I have affixed my signature.

VICENTE SANCHEZ.
